VALVE HEAD

Emory C. Williams, Fort Payne, Ala.

Application February 6, 1948, Serial No. 6,761

6 Claims. (Cl. 277—13)

1

This invention relates to a valve head construction, and more particularly, to a valve head particularly adapted to control the flow of liquid in a toilet, although quite possibly, the valve head has application to other devices as well.

The present application is a continuation in part of my previous application, covering a toilet, filed June 29, 1945, Serial Number 602,268, now Patent Number 2,443,214, issued June 15, 1948.

The application in question covers a toilet construction wherein the toilet normally is enclosed within a wall communicating between adjacent rooms, and is adapted to swing on its mounting into either room.

The swinging toilet of the parent application operates, by its swinging into and out of the wall, a valve, and the present application relates to an improved construction for the valve.

The primary object of the present invention is to provide a valve head of far greater simplicity than that shown in the parent application, which will nevertheless discharge with full efficiency all the functions required of the original valve head.

With the foregoing and other objects in view which will appear as the description proceeds, the invention consists of certain novel details of construction and combinations of parts, herein-after more fully described and pointed out in the claims, it being understood that changes may be made in the construction and arrangement of parts without departing from the spirit of the invention as claimed.

Referring to the drawings

Figure 1 is a longitudinal section through the valve head, in which parts remain in elevation, mounted in a wall in association with a reservoir or tank, the position of the parts of the valve being shown as they appear when the toilet is swung out of the wall for use.

Figure 2 is an enlarged section taken substantially on line 2—2 of Figure 1.

Figure 3 is an enlarged section taken substantially on line 3—3 of Figure 1, the valve position being shown the same as in Figure 1.

Figure 4 is an enlarged longitudinal section through the valve head, the parts of the valve being shown in the position they assume when the toilet is enclosed within the wall and not in use.

Figure 5 is another section taken on line 3—3 of Figure 1, the parts being shown in the same position as in Figure 4.

Figure 6 is a section taken substantially on line 6—6 of Figure 1.

2

Referring to the drawings in detail, the reference numeral 28 is applied to an outlet pipe section. An inlet or feed pipe is designated 39, a reservoir or tank is 42, and a pipe 41 provides constant communication between tank 42 and the valve casing. These particular numerals refer to corresponding parts in the parent case, and by reference to Figure 3 of the parent case, the location of the valve of the present invention, and the structure whose place it takes, can be immediately noted.

In the present invention, a valve casing 5 has a main or outlet valve chamber 6 and a secondary or inlet valve chamber 7. These are in communication. The inlet feed pipe 39 opens into inlet valve chamber 7. The outlet valve chamber not only communicates at one end with the inlet chamber 7, but at its top opens into pipe 41 leading to the reservoir 42, while at its bottom it opens into the outlet pipe section 28.

The valve casing 5 and the outlet pipe section 28 are relatively rotatable members. As applied to a swinging toilet of the type described in the parent application, it is the outlet pipe section 28 which has rotatable movement, while the valve casing 5 is mounted stationarily. I can conceive of other applications, quite possibly not used in conjunction with a swinging toilet, wherein the valve casing might be the rotatable member, with the pipe section stationary, or wherein both members are mounted for rotatable movement. In any event, the same valve operation would result, as will be apparent from the description to be provided hereinafter.

For the purpose of providing a leak-tight connection between the casing and pipe section, while yet permitting relative rotation, the pipe section is provided at its upper end with an outwardly directed annular flange or shoulder 8, while the casing is provided with an inwardly directed flange or shoulder 9. Packing 10 is interposed between the flanges, and thus the parts are permitted relative rotation while yet providing a leak-tight connection.

Extending into the outlet valve chamber 6, from the end of the pipe section 28, are diametrically opposed pins 11. As applied to a swinging toilet, not shown, to which outlet pipe section 28 is fixedly connected, pins 11 are in line with a line drawn longitudinally through the center of the hopper. If valve casing 5 extends longitudinally of the wall in which the hopper is normally enclosed, it becomes apparent, by noting the position of pins 11 in Figure 3, that this is their position when the hopper is swung out of the wall in either direc-

tion, and is disposed at right angles to the wall, for use. Figure 5 shows pins 11 in their position when the hopper is enclosed within the wall and is not in use.

Also carried by the top of the outlet pipe section 28, and extending into the chamber 6, are diametrically opposed lugs 12, which are equidistant from the pins 11, and which preferably are smaller than the pins.

Extending across the open end of the pipe section, between pins 11, is a cross member 13, the purpose of which will be apparent.

The invention embodies the main or outlet valve, compositely formed of co-acting semi-circular valve blocks 14 and 15. These are so proportioned that when they are brought together into engagement, as in Figures 1 and 3, they close off the valve chamber 6 from the outlet pipe section 28. When spread apart, however, as in Figure 4 and Figure 5, the valve blocks permit communication between the chamber and pipe section.

Rotatable movement of the pipe section 28 relative to the valve casing is adapted to spread the valve blocks apart, or draw them together, as the case may be. When the hopper, not shown, is swung fully out of its enclosure, in either direction, the valve blocks are brought into engagement with each other (Figure 3) so as to close communication between the outlet valve chamber and the pipe section. When the hopper is positioned fully within its enclosure, the valve blocks will have been spread apart (Figures 4 and 5).

This is accomplished as follows. The under side of valve block 14 is formed with a groove 16 adapted to receive either pin 11. This groove is of generally curved appearance, lying close to the straight or inner side of the valve block, and for the greatest length of said inner side, as clearly seen from Figures 3 and 5. The groove opens at both ends, and has an intermediate portion curved close to the straight side of the block with the end portions being disposed somewhat further away from said side.

Block 15 has a similar groove 17 formed in its under side, and when the valve blocks are in engagement with each other, the ends of both grooves communicate. In this position of the valve blocks, the pins 11 are positioned directly in the line of engagement of the blocks so as to be disposed partly in both grooves.

In the under side of blocks 14 and 15, there are also formed semi-circular outer grooves 18 and 19 respectively. These are disposed close to the outer, curved sides of the respective blocks. These grooves receive lugs 12. When blocks 14 and 15 are in engagement with each other, the grooves 18 and 19 also communicate at their ends, as seen from Figure 3.

When the blocks are spread apart as in Figure 5, rotation of the pipe section 28 through 90° draws the blocks together. By extending the ends of the grooves 16 and 17 away from the direction of rotatable movement, the blocks are brought together more rapidly than would be the case if the grooves were straight.

During this movement of the pipe section, the lugs 12 will enter the outer grooves 18 and 19. As pins 11 move into the ends of the inner grooves, pins 11 will no longer act to bring the blocks together. However, lugs 12 complete the task, and when the lugs 12 are in the position shown in Figure 3, they will have fully locked the blocks together. Cross member 13 of the pipe section will be positioned directly below the line of engage-

ment, and assist in providing a proper seal against leakage.

One end of the valve casing 5 is bored to permit slidable reciprocation of a guide rod 20 mounted therein. One end of the guide rod is threaded for engagement in a threaded bore 21 of valve block 14.

A valve rod 22 is extended through the opening communicating between the outlet and inlet valve chambers, but does not close off the opening against the passage of liquid. The valve rod 22 is also threaded at one end for engagement in the bore 21 of block 14. Block 15 has a smooth bore to permit the valve rod to be slidably reciprocated therethrough.

The end of the valve rod 22 that projects into the inlet chamber 7 is provided with an inlet valve 23 which can be detachable if desired, as shown in Figure 5. Inlet valve 23 has longitudinal relief passages 24. The purpose of these is to permit the escape of liquid which might otherwise be trapped in the inlet chamber 7 during reciprocation of the inlet valve.

The valve head is readily assembled as follows. Outlet pipe section 28, equipped with pins 11 and lugs 12, is dropped down through the large opening at the top of the valve casing 5 until its end is flush with the floor of the outlet valve chamber 6. Prior to lowering the pipe section 28 in the manner described, the pair of valve blocks is loosely positioned on the pins 11 and lugs 12. This is done with the pins and lugs in the position shown in Figure 3.

With the blocks seated on its upper end in this manner, the pipe section is now lowered as stated. Guide rod 20 is now extended through the bore of the valve casing and is threaded into block 14, the outer end of the guide rod being formed with a kerf 25 adapted to receive a screw driver bit.

The inlet valve rod 22, equipped with its inlet valve 23, is now extended through the bore of block 15, and is threaded into bore 21 of block 14. The outer end of the inlet valve 23 is formed with a kerf 25 for this purpose.

The operation of the device is as follows. The assembled valve head, connected to pipe 41 and inlet feed pipe 39, and joined through suitable unions to pipe members extending from opposite sides of the enclosure wall, will have its parts in the positions shown in Figures 1, 2 and 3, when the hopper is swung outwardly from its enclosure and is in use. At this time, the main or outlet valve is seated over the outlet pipe section, but the inlet valve 23 is permitting water to enter the inlet valve chamber 7 through the feed pipe 39. The water so entering is forced into the main valve chamber 6 and fills reservoir 42.

When the hopper is swung back into the enclosure, it partially rotates the pipe section 28, and this opens the main valve as shown in Figures 4 and 5, at the same time moving the inlet valve 23 into a position closing feed pipe 39. As a result, the reservoir 42 is emptied, and the water stored in the tank is released to flow by gravity through the outlet valve chamber 6 and downwardly through pipe section 28 into the hopper at any suitable point. It flows outwardly from the hopper into a soil pipe, not shown.

It may be noted that the operation is the same whether the hopper is swung from its enclosure in one direction, or in the opposite direction.

What is claimed is:

1. A valve head comprising a casing formed with a chamber having spaced openings, spread-

able valve blocks in the chamber and adapted to close flow through one opening when brought against each other, and to permit flow through said opening when spread apart, means responsive to movement of one of the blocks adapted to close the other opening when the blocks are spread, and to close said last-named opening when the blocks are brought together, and means for spreading the blocks and bringing them together.

2. A valve head as in claim 1, and wherein the means last named comprises a pipe section connected to the casing for relative rotatable movement and communicating with the chamber through the first-named opening, said pipe section having projections engaging the blocks and adapted to spread them apart and bring them together, on rotatable movement of the pipe section relative to the casing.

3. A valve head as in claim 1, and wherein the last-named means comprises a pipe section connected to the casing for rotatable movement relative to the casing, the pipe section including projections extending into the chamber, there being grooves formed in one face of each block adapted to receive said projections.

4. A valve head as in claim 1, and wherein the means responsive to movement of one of the blocks comprises a valve rod secured to one of the blocks, and a valve secured to the valve rod and adapted to seat over the last-named opening.

5. A valve head as in claim 1, and wherein the means responsive to movement of one block com-

prises a valve rod secured to said block, and slideable in the other block, and a valve secured to the valve rod and adapted to seat over the last-named opening.

5 6. A valve head including a casing having a chamber provided with an inflow opening, an outflow opening, and a two-way flow opening, spreadable valve blocks in the chamber and adapted to close the outflow opening when brought against each other and to open the outflow opening when spread apart, means responsive to movement of one of the blocks adapted to close the inflow opening when the blocks are spread and to open the inflow opening when the blocks are brought together, and means for spreading the blocks apart and bringing them together, whereby, when the blocks are together, to permit flow into the chamber through the inflow opening, said flow leaving the chamber by way of the two-way opening, and when the blocks are spread, to permit flow into the chamber through the two-way opening, said flow leaving the chamber by way of the outflow opening.
